UNITED STATES PATENT OFFICE.

SAMUEL HUMPHREY, OF INDIANA HARBOR, INDIANA.

RAIL.

1,193,150.

Specification of Letters Patent.

Patented Aug. 1, 1916.

Application filed May 15, 1916. Serial No. 97,636.

To all whom it may concern:

Be it known that I, SAMUEL HUMPHREY, a citizen of the United States, residing at Indiana Harbor, in the county of Lake and State of Indiana, have invented certain new and useful Improvements in Rails; and I do declare the following to be a full, clear, and exact description of the invention, such as will enable others skilled in the art to 10 which it appertains to make and use the same.

This invention relates generally to railroad construction, and more particularly to certain new and useful improvements in 15 rails.

The principal object of the invention is to provide a rail for railroads having improved means for preventing the car or train from leaving the same.

20 Another object of the invention is to provide a means for overcoming this difficulty, which may be removably or firmly attached to a rail of the usual construction, without any special adaptation.

25 A still further object resides in the provision of a device of this character which will be simple, strong, durable and comparatively inexpensive in construction, efficient and reliable in operation, and well 30 adapted to the purpose for which it is designed.

With these and other objects in view, the invention consists of certain novel features of construction, and the combination and 35 arrangement of parts as will be hereinafter fully described and claimed.

In the accompanying drawings, forming 40 a part of the specification, and in which similar reference characters designate like parts throughout the several views, Figure 1 is a transverse sectional view through a track provided with rails constructed in accordance with this invention in co-operative relation with a pair of the usual truck 45 wheels of a railway car; Fig. 2 is a side elevation of a modified form of the invention; and Fig. 3 is a transverse sectional view taken on the plane of the line 3—3 of Fig. 2.

50 Referring more particularly to the drawings, the reference numeral 1 designates a rail provided with the usual head 2 connected by a web 3 with a base 4, the latter being secured in the usual manner to the 55 ties of the road-bed. The outer side of the head 2 of the rail is provided with a flange

5, which extends upwardly therefrom and has its upper edge disposed in a plane above the upper edge of said head.

In Figs. 2 and 3 of the drawings, an ordinary T-rail is shown, the head 6 of which is substantially square shaped in cross section, and provided with transversely extending apertures 7 near its lower edge. It is, however, to be understood that the exact 60 configuration of the head 6 is immaterial so long as its outer side is substantially flat or shaped to engage the flat portion arranged on the inner side of a detachable flange 8, said flat portion being arranged in abutting 65 relation to the flat side of the head 6. This detachable flange 8 projects upwardly and has its upper edge disposed in a plane above the upper edge of the head 6 to provide the same general structure in cross section as 70 that shown by the simpler form shown in Fig. 1 of the drawings. The flange 8 is provided with apertures 9 near its lower edge, said apertures 9 being alined with the apertures 7 in the head 6 of the rail and receiving therein suitable clamping elements in the form of ordinary bolts 10, whereby 75 said flange 8 is firmly but removably attached to the rail. By this construction it may be seen that the device may be used or 80 connected with rails already in use, as may be found very convenient.

It will be obvious that any tendency of the wheels of the cars of leaving a track composed of rails constructed in accordance 90 with this invention will be counteracted, as the outer edges of the treads of the wheels will bear or tend to bear against the inner sides of the flanges 8, thus preventing the wheel flanges from mounting the rail. 95

From the foregoing description taken in connection with the accompanying drawings, the construction and operation of the device will be readily understood without a more extended explanation. 100

As various changes in form, proportion and the minor details of construction may be resorted to without departing from the spirit of this invention, I do not wish to be limited to the construction herein shown and described other than that set forth in the appended claim. 105

I claim as my invention:

The combination with a T-rail provided with the usual head having a substantially flat outer side, of a flange having a flat portion on one of its sides arranged in abutting 110

relation to the flat side of the head of said rail, said flange projecting upwardly and having its upper edge disposed in a plane above the upper edge of said head, and
5 clamping elements extending through said flange and head of said rail for removably attaching the same to the latter.

In testimony whereof I have hereunto set my hand in presence of two subscribing witnesses.

SAMUEL HUMPHREY.
